Primary Examiner — Mark Goodwin(74) *Attorney, Agent, or Firm* — Boyle Fredrickson, S.C.(57) **CLAIM**

The ornamental design for a walk-behind compaction roller, as shown and described.

DESCRIPTION

FIG. 1 is an isometric view of a walk-behind compaction roller incorporating our new design, viewed from above, in front of, and from the right side of the compaction roller;

FIG. 2 is a right side elevation view thereof;

FIG. 3 is a left side elevation view thereof;

FIG. 4 is front end elevation view thereof;

FIG. 5 is a rear end elevation view thereof;

FIG. 6 is a top plan view thereof; and,

FIG. 7 is a bottom plan view thereof.

The broken lines in the drawings are for illustrative purposes only and form no part of the claimed design.
